UNITED STATES PATENT OFFICE.

WILLIAM H. H. SAUNDERS, OF TROY, NEW YORK.

COMBINED BLACKING BRUSH AND BOX.

Specification forming part of Letters Patent No. **59,461**, dated November 6, 1866.

To all whom it may concern:

Be it known that I, WILLIAM H. H. SAUNDERS, of the city of Troy, in the county of Rensselaer and State of New York, have invented a new and Improved Blacking-Brush and Blacking-Box Holder; and I do hereby declare that the following is a full, clear, and exact description of the same, reference being hereby had to the accompanying drawings, which make and form a part of this specification.

Like letters represent and refer to like or corresponding parts.

Figure 1 is a perspective view of my said combined blacking-brush and blacking-box holder as it would appear when the several parts are combined together for the purpose of putting the same away when not in use. Fig. 2 is a view showing the brush by which the blacking is applied to the boot or shoe. Fig. 3 is a view showing my said brush and blacking-box holder with the cover or applying-brush B removed. Fig. 4 shows the polishing-brush A, with the handle C and blacking-box H' removed therefrom; also showing the screw D and the recess L, wherein the blacking-box H' is placed; also the pins M and N, each more fully hereinafter described and set forth. Fig. 5 shows the handle C, which is fastened to the brush A by the screw D, in the manner substantially as hereinafter more fully described and set forth. Figs. 6 and 7 show the blacking-box H' and cover I, which are placed in the recess on the back of the brush A, in the manner and for the purposes hereinafter described and set forth.

The nature of my said invention and improvement consists in the employment of an ordinary polishing-brush, A, with the recess L in the top thereof, in which is placed a blacking-box, and made fast therein by the means fully hereinafter described and set forth. It also consists in so constructing a blacking-brush that when the same is put away and not in use the blacking-box will be inclosed between the two brushes, and the whole combined together substantially in the manner and for the purposes more fully described and set forth.

To enable others skilled in the art to which my invention relates to make and use the same, I will here proceed to describe the construction

and operation thereof, which are as follows, to wit:

I construct my said improved blacking-brush of any size desired, and of any material deemed best. The said polishing-brush A has a recess, K, in the top thereof, into which the handle C is made fast by means of the thumb-screw D. It also has a concave recess, L, in which the blacking-box is placed and made fast by the means hereinafter described.

I prefer to use, in connection with my said brush, a blacking-box constructed substantially as seen at Fig. 6, as it possesses advantages over the box now ordinarily in use, from the fact that all the blacking is used up, and costs less for its manufacture.

J, Fig. 6, is a lip made upon the edge of the blacking-box. When it is desired to fasten a box of blacking upon the said brush A, the thumb-screw D is loosened and the box placed within the recess L, with the lip J toward the said recess K. The handle C is then pushed forward until it presses against the box H'. The thumb-screw D, being then screwed down, will come directly over the lip J of the box H', which, being held at the other side by the pins M and N, will rest firmly in its place, substantially as seen at Fig. 3 in the accompanying drawings.

It is obvious that an ordinary blacking-box may be used in connection with my said brush, the said pins M and N holding it on one side, while the handle C, being pressed against it on the other, will hold it securely in its proper place and position. The pin N may have its head bent a little, and, fitting into a corresponding slot in the box, will more firmly hold the same in its proper place.

The cover or applying-brush B is held in its place on top of the said brush A by means of the pin M, which extends upward and fits into the slot P in the said cover. The handle to the said cover or applying-brush is then pushed under the head of the thumb-screw D, and is thereby held in its proper place and position when not in use.

I, Fig. 7, is the cover to the blacking-box, which can be thrown away after the box is fastened to the brush, as hereinbefore described, as the cover or applying-brush B will act as a cover when not in use.

When it is desired to use my said brush and

box combined, the said cover or applying-brush is removed from the said polishing-brush A. The said brush A serves as a holder for the blacking-box H', thereby avoiding the soiling of the hands while using the same. The blacking is put upon the boot or shoe by means of the brush B, using the blacking from the box H', and the brush A is used for the polishing-brush.

Having thus described the nature of my said invention, what I claim, and desire to secure by Letters Patent, is—

1. The combination of the removable and adjustable handle C, having a slot-mortise in the front end thereof, so as to receive the thumb-screw D, with the brush A, containing the recess K, and with the said thumb-screw D, each being arranged in the manner and for the purposes substantially as herein described and set forth.

2. The employment of the polishing-brush A, containing the concave or other shaped blacking-receptacle H, or any equivalent therefor, in combination with the cover and applying-brush B, constructed, arranged, and operated in the manner and for the purposes substantially as herein described and set forth.

3. The combination of the polishing-brush A and box H', and cover or applying-brush B, in the manner and for the purposes substantially as herein described and set forth.

In testimony whereof I have on this 6th day of February, A. D. 1866, hereunto set my hand.

WM. H. H. SAUNDERS.
